UNITED STATES PATENT OFFICE.

GEORGE W. O'KEEFFE, OF DORCHESTER, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

THERMAL ELECTRIC-CIRCUIT CONTROLLER.

Application filed April 28, 1922. Serial No. 557,055.

To all whom it may concern:

Be it known that I, GEORGE W. O'KEEFFE, a citizen of the United States, residing at Dorchester, in the county of Suffolk and 5 State of Massachusetts, have invented an Improvement in Thermal Electric-Circuit Controllers, of which the following is a specification.

This invention relates to thermal electric 10 circuit controllers of the type wherein the thermally expansible element, and associated elements, are contained within a tubular enclosing casing, and is adapted to be received in spring clips in a manner similar to 15 a cartridge type enclosed electric fuse.

An object of this invention is generally to 20 improve the construction and operation of controllers of the above type and, specifically, this invention is intended as an improvement on the invention disclosed in my co-pending application filed April 28, 1922, Serial No. 557,054.

Fig. 1 is a side view of the thermal electric circuit controller embodying the invention.

Fig. 2 is an axial sectional elevation of the controller as mounted in spring clips.

Fig. 3 is a plan view of the controller.

Fig. 4 is a sectional elevation of the controller without the electrical heating element.

Fig. 5 is a left hand end view of the controller of Fig. 1.

Fig. 6 is a right hand end view of the controller of Fig. 1.

Fig. 7 is a cross-section of the controller along lines 7—7 of Fig. 2 with the thermal element and fixed contact member arranged to control a normally closed control circuit.

Fig. 8 is a view similar to Fig. 7 with the parts arranged to control a normally open circuit.

Fig. 9 is a sectional elevation of an end cap with attached thermal element.

Fig. 10 is a side view of the insulating plug for the fixed terminal member.

Fig. 11 is a plan view of an end cap and illustrates the slot in the side wall thereof.

Fig. 12 is a plan view of the tubular casing and illustrates the slot in the end thereof.

Fig. 13 is a diagram of a typical control circuit including the circuit controller.

Fig. 14 is a transverse sectional view 55 through a convolution of the thermal element and illustrating more particularly the construction of the thermostatic material composing the element.

As here shown, the thermal electric circuit controller embodying the invention includes the tubular enclosing casing 10 of insulating material and the end caps 11 and 12 which are received on the ends of and enclose said casing and, in the final assembly of the controller, are adapted, preferably, to be permanently secured to the casing by suitable means, as by crimping them over the ends of the casing.

The thermally expansible element may 70 comprise the tubular coil 13 of thermostatic or other suitable expansible material having the inner end portion 14 thereof extended laterally of the coil and provided with the contact points 15 disposed on opposite sides of said end portion and adapted for engagement with a fixed terminal or contact member hereinafter to be described. Said tubular coil may be carried by and electrically connected with the end cap 11 by 75 suitable means and, as here shown, the outer end portion 16 is secured by suitable means, as solder, to the tube 17, which latter is inserted within the outer end of said coil. Said tube may have the reduced outer end portion 18 which is received within an eccentrically disposed aperture 19 in the end wall of the end cap 11; and said end portion may be expanded over the end wall to 80 secure the thermal element permanently to 85 the end cap.

The thermostatic material comprising said expansible element may comprise a strip or sheet composed of two metals having 90 dissimilar expansion coefficients and united together in any suitable manner to form, in effect, a single sheet or strip having marked susceptibility to temperature variations. Fig. 14 illustrates a cross-sectional view 100 taken through one of the convolutions of the thermal element and illustrating the dissimilar metals *x* and *y*.

It is an object of this invention to pro-

vide a terminal or fixed contact member which extends laterally from the casing of the controller and to which a lead of the control circuit is adapted to be connected. 5 For this purpose, a plug 20 of insulating material is snugly received within and is supported by the casing 10 in front of the end cap 12; and said plug may have the peripheral outstanding flange 21 received 10 between the end of the casing 10 and the end cap 12 whereby to hold the plug axially in position within the casing. Said plug is formed with the lateral extension 22 which projects externally substantially beyond the 15 casing and the end cap 12 and forms an external insulating support for the fixed contact member. The side wall of the end cap 12 is formed with the recess 23 in which said extension is received and the side wall of the enclosing casing 10 is formed with a similar recess 24 in which said extension is also received; and said extension is preferably snugly received in both aligned recesses whereby to lock said plug and end 20 cap and casing together so far as relative angular motion is concerned.

The fixed terminal or contact member comprises the L-shaped bar 25 imbedded within said plug 20 beneath the lateral surface thereof and having one leg 26 extended laterally and externally beyond the casing through the extension 22 of the plug. Connecting means, as the screw 27, may be carried by said leg 26 beyond the casing for 30 connection with a lead of the control circuit. Said bar 25 is also formed with the leg 28 which is extended longitudinally within the casing 10 adjacent and in co-operative relation with the movable end of 35 the thermal element 13. Said leg 28 may have an adjustable contact point, as the screw 29, threaded in said leg which is adapted to be engaged by one or the other of the contact points 15 to control the 40 control circuit including the fixed contact member and thermal element.

In Fig. 7, the movable end-portion 14 of the thermal element and the contact member are arranged to control a normally 50 closed control circuit and the thermal element is arranged to move angularly toward the left under the influence of heat and break the control circuit. In Fig. 8, the arrangement is for a normally open control circuit 55 and the thermal element is arranged to move toward the left when heated and close the control circuit.

The free or inner end of the tubular thermal element is rotatably supported in position by the insulating cylindrical projection 30 of the insulating plug 20 which is arranged co-axially with said thermal element and is received loosely therein.

The controller as described is adapted to 60 be assembled as a unit and electrical heat-

ing elements for the thermal element are adapted subsequently to be inserted; and the particular heating element to be inserted will depend upon the current value at which the controller is desired to operate.

The electrical heating element for the thermal element may be in the form of an electrically conducting rod 35. Said rod is disposed within the tubular thermal element and in heat-imparting relation therewith. 70 One end of the rod may be received within the passage 36 in the tube 17 of the thermal element and the other end may be extended through a passage 37 in the insulating plug 20 and an aligned aperture 38 in the end cap 12. The heating element may be permanently secured in place and in electrical connection with said end caps 11 and 12 by suitable means as solder applied to the end cap over the ends of said heating element.

The character of the heating element may vary for the different values of current at which the controller is desired to operate. For relatively large values of current, the 90 heating element may have relatively low resistance and, for lower values of current, a higher resistance. For extremely low values of current, the heating element may be a carbon rod, not necessarily shown.

The contact point 29 of the fixed contact member 25 may be adjusted from without the casing by the insertion of a suitable tool through one or the other of the holes 40 in the side wall of the casing 10; and the relative position of the fixed contact member and movable end of the thermal element may be inspected through the peep hole 41. All holes may be permanently covered by a suitable seal, as the label 42, 95 after the final adjustment is made.

In the assembly of the component parts of the controller it is to be noted that, as the extension 22 of the insulating plug 20 locks together said plug with its fixed contact member, the end cap 12 and the enclosing casing 10, the initial adjustment of the contacts may be made by rotating but a single member, the end cap 11 with its thermal element, in the proper direction.

The end cap 11 and the casing 10 may have witness marks A and B respectively, or other suitable indicia, which may be brought into alignment to indicate the proper operational relation of the relatively movable contact members concealed within the casing.

The controller may be inserted in, and for the protection of, a power circuit 50, see Fig. 13, here shown as having the motor 51 connected therewith, and the fixed contact member 25 of the controller and the thermal element are connected with and arranged to control the control circuit 52 of the switch to effect the opening of said switch when the current in the power circuit 130

cuit exceeds a value above which the heating element of the controller is designed to be effective in heating and operably expanding the thermal element.

5 I claim:

1. A thermal electric circuit controller including the combination of an enclosing casing, metal end caps disposed on the ends of the casing, a movable thermally expansible element contained within the casing and an insulated fixed contact member disposed within the casing in operative relation with said thermally expansible element and extended laterally beyond the casing and 10 through and insulated from one of said end caps and having connecting means for a circuit lead carried by its extended end.

2. A thermal electric circuit controller including the combination of a tubular enclosing casing, metal caps on the ends of the casing, a movable thermally expansible element disposed within the casing, and an insulated fixed contact member disposed within said casing in cooperative relation with 20 said thermally expansible element and extended axially within said casing toward one end thereof and having a terminal portion extended laterally through the tubular casing and the side wall of and insulated from 25 an end cap and having connecting means for a circuit lead carried by its extended end.

3. A thermal electric circuit controller including the combination of an enclosing casing, an end cap on one end of said casing, 35 a thermally expansible element disposed within said casing, an insulated fixed contact member disposed in operative relation with said thermally expansible element, and means to lock together said casing and end 40 cap and contact member in fixed relation.

4. A thermal electric circuit controller including the combination of an enclosing casing, an end cap on one end of said casing, a thermally expansible element disposed 45 within said casing, an insulated fixed contact member disposed in operative relation with said thermally expansible element, and means to lock said casing and end cap and contact member in fixed relation comprising 50 an insulating support for said fixed contact member extended laterally through aligned recesses in said casing and end cap.

5. A thermal electric circuit controller including the combination of an enclosing casing, an end cap on one end of said casing, a thermally expansible element disposed 55 within said casing, an insulated fixed contact member disposed in operative relation with said thermally expansible element, and means to lock said casing and end cap and contact member in fixed relation comprising 60 an insulating support for said fixed contact member extended laterally through aligned recesses in the side wall at the end of said 65 casing and in the side wall of said end cap.

6. A thermal electric circuit controller including the combination of an enclosing casing, an end cap on one end of said casing, a thermally expansible element disposed within said casing, an insulated fixed contact member disposed in operative relation with said thermally expansible element, and means to lock said casing and end cap and contact member in fixed relation comprising 70 an insulating support for said fixed contact member extended laterally through aligned recesses in the side wall at the end of said casing and in the side wall of said end cap, an end cap on the other end of said casing, and electrical heating means disposed in 75 heating relation with said thermally expansible element and electrically connecting said end caps.

7. A thermal electric circuit controller including the combination of an enclosing casing, an end cap on one end of said casing, a thermally expansible element disposed within said casing, an insulated fixed contact member disposed in operative relation with said thermally expansible element, and means to lock said casing and end cap and contact member in fixed relation comprising 80 an insulating plug carrying said fixed contact member received in the end of and supported by said casing, said insulating plug 85 having a lateral projection which extends laterally through aligned passages in said casing and end cap.

8. A thermal electric circuit controller including the combination of an enclosing casing, an end cap on one end of said casing, a thermally expansible element disposed within said casing, an insulated fixed contact member disposed in operative relation with said thermally expansible element, and means to lock said casing and end cap and said contact member in fixed relation comprising 100 an insulating plug carrying said fixed contact member received in the end of and supported by said casing, said insulating plug 105 having a lateral projection surrounding said fixed contact member which extends laterally through aligned passages in the side wall of said casing and the side wall of said end cap.

9. A thermal electric circuit controller including the combination of an enclosing casing, an end cap on the end thereof, an insulated fixed contact member disposed within the casing and extended externally thereof, and means holding all in fixed relation, a thermally expansible element disposed within said casing in operative relation with said fixed contact member, and adjustable supporting means for said expansible element.

10. A thermal electric circuit controller including the combination of an enclosing casing, an end cap on the end thereof, an insulated fixed contact member disposed 120

- within the casing and extended externally thereof, and means holding all in fixed relation, a thermally expansible element disposed within said casing in operative relation with said fixed contact member, and adjustable supporting means for said expansible element comprising a second end cap bearing said expansible element rotatably received on the end of said casing.
- 10 11. A thermal electric circuit controller including the combination of an enclosing casing, an end cap on the end thereof, an insulated fixed contact member disposed within the casing and extended externally there-

of, and means holding all in fixed relation, 15 a thermally expansible element disposed within said casing in operative relation with said fixed contact member, and adjustable supporting means for said expansible element comprising a second end cap having 20 said expansible element rotatably received on the end of said casing and electrical heating means disposed in heating relation with said thermally expansible element and electrically connected with said end caps. 25

In testimony whereof, I have signed my name to this specification.

GEORGE W. O'KEEFFE.
